Application January 14, 1939, Serial No. 250,902
In Switzerland January 28, 1938

6 Claims. (Cl. 176—16)

It is known to make incandescent electric lamp bulbs with a double wall. With such lamps it is often found that the outer bulb becomes excessively hot especially if the volume of the inner 5 bulb is relatively small. In order to avoid this drawback it is known to fill the outer bulb with a gas having a greater heat conductivity than air or to cause a liquid to circulate between the two bulbs.

10 The first method however, is found to be insufficiently effective if it is desired to use inner bulbs of very small volume, while the second necessitates the use of bulky and complicated apparatus. A liquid must be used which leaves 15 no deposit, for example distilled water, and a small pump must be provided for ensuring circulation of this water between the lamp and a cooling device.

20 The chief object of the invention is to obtain very efficient cooling of the inner bulb by simple and automatic means.

25 This object is attained according to the invention by providing between the two walls a liquid in which the inner bulb is immersed, and which only partly fills the space between the two walls, the said liquid boiling during the operation of 30 the lamp and the emitted vapours condensing upon the part of the outer bulb which is above the level of the liquid.

35 When such a lamp is put in operation the filament transmits heat to the wall of the internal bulb which becomes heated and in turn transmits the heat received to the liquid. The hotter this liquid becomes, the greater the increase in its vapour pressure. The vapours emitted condense upon the wall of the external bulb which is cooled by the surrounding air. As the pressure continues to rise, the heat transmission from the inner to the outer bulb increases. The nature of 40 the liquid and the dimensions of the external bulb must be so chosen that under ordinary working conditions the temperature of the inner bulb is sufficiently low to prevent the liberation of a gas from said bulb which would attack the filament, and that the vapour pressure inside the outer bulb does not become such as to cause it to burst.

45 In order to facilitate the diffusion of the vapour from the surface of the liquid to the walls which 50 act as condensers, it is advisable not to leave in the outer bulb too high a pressure of non-condensable gas. However, too high a vacuum should not be created if boiling of the liquid accompanied by violent sudden jerks therein are to be avoided.

The liquid adapted must be transparent to the useful rays emitted by the filament, it must not attack the walls of the two bulbs and must not freeze too easily. Further, it must not produce, under the action of the prolonged heating to 5 which it is exposed during working, a quantity of volatile decomposition products which would dangerously increase the internal pressure in the bulb, nor form coloured products which would intercept the light.

10 Good results are obtained when using saturated hydrocarbons or mixtures of such hydrocarbons, such as vaseline oil. This liquid may not at first sight appear very suitable owing to its low heat conductivity. In use it has, however, 15 been found very satisfactory owing to its high co-efficient of expansion which results in large convection currents thus facilitating boiling in the upper portion of the liquid.

20 In order to obtain completely even boiling, a porous substance for initiating the formation of gas bubbles may be provided near the top of the liquid. Further, the convection currents may be assisted by suitably located partitions.

25 Vaseline oil has the further advantage of being sufficiently transparent to infra-red rays which is very advantageous for lamps for general lighting where it is of advantage not to retain in the lighting apparatus, the heat due 30 to the radiated energy.

35 On the contrary, in certain cases the infra-red energy emitted produces injurious overheating. Thus, for example, in lamps used in cinematographic projectors the infra-red rays abnormally heat the condenser lens of the apparatus and also the film. According to a further feature of the invention use is in such cases made of a liquid absorbing the infra-red, for example water to which has been added a few thousandth parts of copper sulphate. This liquid transmits 40 the major portion of the energy to the upper part of the outer bulb and the light rays emerging from the lamp will contain practically nothing beyond the useful rays.

45 In the same way a coloured liquid may be used for correcting the light emitted by the filament so as to obtain a whiter light or a coloured light. Use can also be made of a luminescent liquid. The unused rays (ultra-violet) will be absorbed by the liquid and transformed into 50 visible rays.

55 The upper portion of the outer bulb may be so shaped and can be of such a nature as to facilitate the heat exchange. For example in the case of projection lamps in which the upward light

rays are not used, the upper portion of the outer bulb could be made of metal. This metal part can carry any known cooling means (fins, tubular shaves, etc.). This cooling can be accelerated by means of a current of air or water circulation.

If the lamps according to the present invention were put in operation in an over heated apparatus, the pressure in the outer bulb might rise abnormally. This risk is avoided by providing a fuse which interrupts the current when the temperature of the liquid becomes excessive.

For certain lamps, for example, projection lamps the luminous flux must be directed. The two bulbs can then be so shaped that the liquid between them constitutes the first element of an optical projection system intended to direct the light.

For high power lamps the outer bulb can be made detachable so that in case of the filament breaking only the inner bulb need be replaced.

Figures 1, 2 and 3 of the accompanying drawings show diagrammatically and by way of example two embodiments of the invention.

Figure 1 represents a xenon-and nitrogen-filled incandescent lamp bulb having a double coiled tungsten filament. The inner bulb *i* is immersed in vaseline oil. After this oil has been placed in the outer bulb *E* the latter is filled with nitrogen at a pressure of 1 centimetre of mercury. During working the oil vapours condense upon the wall of the outer bulb *E*. The fuse *f*₁ is a guard against excessive heating. The fuse *f*₂ melts on the occurrence of an excess voltage due to arcing.

Figures 2 and 3 represent a projection lamp according to the invention. As shown in Figure 3 which is a section on the line *a*—*b* Figure 2 the two bulbs are so shaped that a large portion of

the light is concentrated upon the condenser lens of the projection apparatus.

The ring of porous substance *P* ensures regular boiling in the upper part of the liquid. The lower part of the outer bulb *E* is of glass up to the line *S*, and the upper part is of metal. This metal carries the fins *L*. According to circumstances these fins can be enclosed in the projector so as to give them the benefit of the air current from the fan which is normally provided in many projectors or they can be placed in a region above the normal height of the projector in order to liberate the heat outside the apparatus.

I claim:

1. A double-walled electric incandescent lamp having a liquid which only partly fills the space between the two walls, the inner bulb being immersed in the said liquid which during operation of the lamp, boils and emits vapours which condense upon the part of the outer bulb which is above the level of the liquid.

2. A lamp according to claim 1, wherein vaseline oil is used as the liquid between the two bulbs.

3. A lamp according to claim 1, wherein a liquid is used which absorbs the undesired rays.

4. A lamp according to claim 1, wherein a luminescent liquid is used.

5. A lamp according to claim 1, wherein the two bulbs are so arranged relatively to each other that the liquid constitutes an optical element for distributing the rays emitted.

6. A lamp according to claim 1 provided with a fuse which is adapted to interrupt the current if the temperature of the liquid becomes too high.

EDOUARD GOMONET.
